UNITED STATES PATENT OFFICE.

F CORTEZ WILSON, OF CHICAGO, ILLINOIS.

TENT-HEATER.

SPECIFICATION forming part of Letters Patent No. 568,393, dated September 29, 1896.

Application filed April 24, 1896. Serial No. 588,863. (No model.)

To all whom it may concern:

Be it known that I, F CORTEZ WILSON, of Chicago, in the county of Cook and State of Illinois, have invented certain new and useful Improvements in Heaters, of which the following is a specification.

My invention relates to improvements in tent-heaters or similar stoves of that class consisting simply of a closed or so-called "air-tight" box, usually having but a single compartment, which constitutes at once both the fire-box and ash-pit, and in which the smoke and draft flues and fuel-door open out at the top of the box, so that the heater may be set down anywhere and among inflammable materials without danger of their ignition by the escape of hot coals or flame from the fire within the heater.

The object of the invention is to provide such a heater of improved and simplified construction and one particularly adapted for use as a receptacle within which camp equipage or other articles may be packed for transportation and readily locked against the intermeddling of unauthorized persons.

In the accompanying drawings, Figure 1 is a perspective view of the heater. Fig. 2 is a top plan view thereof. Fig. 3 is a sectional elevation on line 3 3 of Fig. 2. Fig. 4 is a sectional detail showing the manner of securing the fire door or cover at its rear edge.

In said drawings, A designates the heater as a whole. It consists of a sheet-metal box conveniently made of rectangular form and without openings of any kind in its side and bottom walls. The top wall comprises a fixed portion A' and a hinged or removable lid or cover A², that is provided with locking devices, consisting in this instance of a hasp a, fitting over a staple a', which is located on the adjacent side wall of the box and through which any suitable padlock or the like may be passed. The rear edge a² of the cover is shown as conveniently held in place by being bent downward to project beneath the adjacent front edge a³ of the fixed top wall A', and may thus be either swung upwardly, as on a hinge, when the hasp a' is released, or may be lifted entirely clear of the box if so desired. The permanent top wall A' is provided near one end with an aperture a⁴ of

suitable size to receive the lower end of an ordinary smoke pipe or flue B, and in an opposite corner is provided with a draft-opening a⁵, having a pivoted cover or slide a⁶, which is held, when closed, by a clip a⁷. A vertical partition-wall A⁸ is arranged to cross the corner of the box just outside of the aperture a⁵, and thus forms a downdraft-flue C, which opens into the main compartment near the bottom of the box, the partition A⁸ terminating at this end a short distance above the bottom and being further herein shown as provided with one or more draft-openings a⁹.

When in use as a heater, a fire of any available fuel is kindled in the box and is supplied with air through the flue C, the products of combustion passing off through the smoke-pipe B and the draft being regulated by the slide a⁶.

The pipe B is supported within the aperture a⁴ by a perforated plate or grating a⁹, which is secured at its edges to the walls of the box and extends beneath the aperture a⁴ a short distance below the top wall A' in such a manner as to cut off communication with the interior of the box except through its perforations or meshes. This plate or grating serves a threefold purpose. It forms a support for the pipe B, and thus enables the top wall of the heater to be made flush and unobstructed by the upwardly-projecting flange or collar, which is ordinarily provided about the smoke-flue opening for the pipe to fit over. It forms an arrester for the sparks, which otherwise might pass up the flue and set fire to the tent or other neighboring property, and it effectually closes the aperture a⁴, so that when the stove is used as a receptacle the locking of the door A² secures the package against intrusion without any special closure for the smoke-flue.

The heater thus described is simple and inexpensive in construction and effective in operation. The draft may be controlled and the fire regulated with great nicety by the slide which covers the draft-aperture, and there is found to be no tendency for smoke to escape into the room. The smoke-pipe B will ordinarily be made in telescoping sections of proper length to be packed within the stove, as shown in dotted lines in Fig. 2,

during transportation or storage. The single compartment of the box forms a capacious receptacle, and the peculiar features of construction described render the package safe from molestation when the door is once locked.

5 I claim as my invention—

1. A heater consisting of a closed box provided with a cover, a smoke-flue opening, and a grating extending beneath said opening to support the pipe and prevent access to the box through said opening, substantially as described.

2. A heater consisting of a closed box provided with a cover, a smoke-flue opening, a grating extending beneath said opening to support the pipe and prevent access to the box through said opening, a draft-aperture in the top of the box and a flue extending downwardly from said draft-aperture to the

lower part of the box, substantially as described.

3. A heater consisting of a closed box provided with a cover and smoke-flue aperture, a draft-opening in the top wall of the box in the corner thereof, a vertical partition extending downwardly across said corner to a point adjacent to the bottom of the box to form a downdraft-flue and a cover for said draft-aperture, substantially as described.

In testimony that I claim the foregoing as my invention I affix my signature, in presence of two witnesses, this 21st day of April, A. D. 1896.

F CORTEZ WILSON.
